UNITED STATES PATENT OFFICE.

ISAAC E. PALMER, OF MIDDLETOWN, CONNECTICUT.

DESIGN FOR A FABRIC FOR HAMMOCKS.

SPECIFICATION forming part of Design No. 36,120, dated October 21, 1902.

Application filed August 30, 1902. Serial No. 121,701. Term of patent 14 years.

To all whom it may concern:

Be it known that I, ISAAC E. PALMER, a citizen of the United States, and a resident of Middletown, in the county of Middlesex and State of Connecticut, have invented a new, original, and ornamental Design for a Fabric for Hammocks, of which the following is a specification.

The essential feature of my design consists in a fabric for hammocks ornamented by a series of heart-shaped figures united by sheaf-like figures and having bouquet-like figures extending from the base of the heart-shaped figures into the space inclosed by the figures.

In the accompanying drawing, which illustrates my invention, the heart-shaped figures are denoted by a, the sheaf-like figures connecting the heart-shaped figures by b, and the bouquet-like figures extending within the heart-shaped figures by c.

What I claim is—

The ornamental design for a fabric for hammocks, substantially as shown and described.

In testimony that I claim the foregoing as my invention I have signed my name, in presence of two witnesses, this 26th day of August, 1902.
